SOUND DISTRIBUTING PANEL AND BAFFLE
FOR RADIO LOUDSPEAKERS

William J. Maxwell, New York, N. Y.

Application December 14, 1935, Serial No. 54,406

16 Claims. (Cl. 181—31)

This invention relates to new and useful improvements in a sound propagating, mixing, regulating and distributing sound board, panel, baffle, or other appliance, suitable for increasing, regulating, modifying, amplifying or improving the tones and other qualities of radio vibrations or sounds which are transmitted in, through or over loud speakers.

One of the means or methods for creating such an improvement and enabling such sounds or waves to be improved in tone, quality, resonance, volume, or to be modified and regulated, is the construction of a sound board, panel, baffle, or other appliance, constructed of various thicknesses, and tapering gradually from a central thick area to the edges thereof, and an arrangement where the radio or the loud speaker or other substitute for a loud speaker, or for any other appliance having the same or a similar function, is associated with or attached upon the thick portion of the sound board, panel baffle, or other appliance, so that the sounds therefrom are propagated, regulated, controlled, modified, amplified, distributed, produced or reproduced into good quality tones, and where undertones of different musical instruments or other instruments producing the sound are heard or better heard than they would be without the use of the apparatus or invention herein described.

Still further, another one of the means or methods to be used, contemplates as a part of the invention, the provision of a tone pin mounted upon a cabinet or other receptacle or container in which a radio is used or contained, engaging against the thick portion of the sound board, panel, baffle, or other appliance, to hold the same under tension, and to produce pressure on the tone pin, to increase or having a tendency to increase its vibrating quality and its resonance, or to increase, multiply, propagate or improve the vibrations or the resonance resulting therefrom.

Another object of the invention, covering one of the means of obtaining the beneficial results above herein set forth, is the construction of a device, appliance or apparatus, as mentioned above, which is simple and durable, and which is capable of being manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a front elevational view of a device constructed according to this invention.

Fig. 2 is a sectional view taken on the line 2—2 of Fig. 1.

Fig. 3 is a fragmentary enlarged detailed view of a portion of Fig. 2.

Fig. 4 is an elevational view looking in the direction of the line 4—4 of Fig. 3.

Fig. 5 is a vertical sectional view of another radio cabinet or container with a sound distributing, sound propagating, sound intensifying, sound regulating, sound amplifying, sound modifying, or sound controlling sound board, panel, baffle, or other appliance, according to a modification of the invention.

Fig. 6 is a fragmentary plan view looking in the direction of the line 6—6 of Fig. 5.

Fig. 7 is a plan view of a combination support and tone pin which may be substituted for the corresponding parts shown in Figs. 5 and 6.

Fig. 8 is another vertical sectional view of a radio cabinet with a distributing panel and baffle according to a modification of the invention.

In the form of the invention illustrated in Figs. 1—4 inclusive there is a cabinet 10, for a radio, which is provided with a panel 11 mounted on the front thereof and constructed according to this invention.

This panel has an intermediate thick portion 11a, and a tapering portion 11b. The panel is under tension by reason of a tone pin 12 as hereinafter further described. For this latter reason, all portions of the panel are not in a common plane, but portions to different sides of the tone pin are disposed in different planes. Preferably, the panel is made of balsa wood and is so designed that certain areas thereof have natural frequencies of vibration at certain predetermined rates. A preferred design would be one in which the portion A of the panel has a variable frequency of natural vibration and is adapted to support the loud speaker of the radio. At the area indicated by the transverse line B, the panel may be designed to have a frequency of 5,000 or more vibrations per second. At the area C the panel may be designed to have a frequency of 3,000 vibrations per second; at the area D, 1,500 vibrations per second; at the area E, 50 or less vibrations per second.

The tone pin 12 is supported or fixed upon a rigid transverse support 13 mounted between the side walls of the cabinet. This tone pin engages against a small reinforcement 14 which is at-

tached upon the inner face of the panel 11. This reinforcement is in the form of a small strip of wood or similar material. A means is provided for urging the panel 11 against the tone pin in a manner so as not to interfere with the vibrations of the panel.

The means mentioned above includes an adjustment screw 15 which threadedly engages through a wooden button 16 disposed on the outside of the panel 11. This adjustment screw has a bracket 17 swivelly mounted on its inner end. A tension spring 18 or other resilient member connects with this bracket and with another bracket 19 swivelly mounted upon a rod 20 which engages through the rigid support 13. The rod 20 has a head 20a upon its outer end which normally engages against the outer side of the support 13. The spring 18 serves to resiliently hold the panel against the tone pin. The resiliency may be of a pre-determined amount or may be changed by screwing in or screwing out the screw 15 to various distances.

A further change of resiliency is possible by the provision of a wedge-shaped member 21 adjustably mounted on the outer face of the support 13. This wedge-shaped member is of step formation and is slideable between a pair of tracks 22. It is adapted to frictionally maintain various positions into which it is placed along the tracks. A stop 23 prevents its complete disengagement from the bottom ends of the tracks. The member 21 is formed with a slot 21a adapted to accommodate the rod 20. The arrangement is such that the rod 20 may be manually drawn outwards to any desired degree and the member 21 moved beneath the rod so that when the rod is released the head of the rod engages a selected step of the member. Thus, more or less tension may be placed upon the spring 18 in addition to the limits of adjustment of the screw 15.

The radio cabinet 10 has a shelf 24 near the top portion thereof upon which the chassis of the radio set may be placed. Several openings 25, 25a, 25b, etc., are formed in the panel 11 through which the controls, such as the knobs of the radio set, may pass. These openings may be decorated by veneered pieces 26 mounted upon the panel to surround the openings.

The panel 11 may be made from one piece of material or from many pieces of material. As shown on the drawing, it is made from two pieces joined at the center of the cabinet 10 along the line 11a. Small reinforcement joining strips 27 are glued or cemented upon the adjacent edges of the panel sections to join them together in a unit.

A loud speaker 28 for the radio is mounted upon the portion A of the panel 11. The speaker is cushioned with felt or rubber against the panel so, as not to transmit foreign vibrations to the panel. The speaker 28 has a flange or rim of speaker portion 28a upon which there is mounted a cushion gasket 29 of felt or rubber which is interposed between the flange or speaker rim and the panel 11. The panel at the portion at which the speaker is attached is formed with an opening 30. A grille 31 is supported upon the outside of the panel around the opening 30. This grille is held spaced from the panel by several cushion washers 32. Bolts 33 engage through the grille 31, the washer 32, and gasket 29, and the flange or rim of speaker 28 to support the grille and the loud speaker upon the panel to keep the speaker and grille in "floating" condition.

The panel 11 may constitute the outer wall of

the radio cabinet or any desired cabinet may be used, for example, one in which there are outer walls. In such cases the panel 11 is disposed within the cabinet and merely acts as a sound distributing panel and baffle for the radio loud speaker. In this case no grille is necessary and cushioning washers should be placed under the screw heads.

In Figs. 5 and 6 a modified form of the invention is disclosed which has specific reference to the tone pin. In this form of the invention there is a rigid support 13b mounted between the walls of the cabinet 10b, but set in from the rear of the cabinet; in fact, the support 13b is located immediately adjacent the front of the cabinet. On this support 13b there is a tone pin 12b in the form of a thin strip of wood which is rigidly attached upon the support 13b and bears against the panel 11b. In other respects this form of the invention is identical to the previous form.

In Fig. 7 another modified form is shown in which there is a rigid support 13c from the sides of which a tone pin 12c projects. This tone pin is integral and is formed of small size at the front end and gradually tapers along the sides to the back end.

In Fig. 8 another modified form of the invention is disclosed in which a cabinet 10d is illustrated provided with a panel 11d. This panel is of similar design as the previous panels and should be provided with a tone pin and resilient member (not shown in this figure) as previously described. The feature of this form of the invention relates to the mounting of the loud speaker. There is a transverse rigid support 35 mounted between the side walls of the cabinet 10b. The field 36 of the loud speaker of the radio is mounted upon a rod or support 37 which is attached upon the support 35. The coil 38 of the loud speaker is mounted upon the panel 11d. With this construction the field is maintained stationary, while the voice coil 38 is capable of vibrating, and correspondingly vibrates the panel.

Wherever the term "panel" is used in describing the various novel features of the invention, it shall be taken to include and mean in addition to its own meaning, any sound board, baffle, or other mechanical appliance to be used for a similar purpose and constructed out of wood of any kind, metal, or of any other composition or matter.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel.

2. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud

speaker mounted on said panel, said panel and tone pin being resiliently associated with each other.

3. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel. Said means for urging the panel against the tone pin including a resilient element.

4. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, said means for urging the panel against the tone pin including a resilient element, supported between the panel and a rigid support mounted upon the cabinet.

5. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, said means for urging the panel against the tone pin including a resilient element, supported between the panel and a rigid support mounted upon the cabinet, one end of said spring being mounted upon a bracket swivelly over a screw adjustably mounted on the panel.

6. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, said means for urging the panel against the tone pin including a resilient element, supported between the panel and a rigid support mounted upon the cabinet, one end of said spring being mounted upon a bracket swivelly over a screw adjustably mounted on the panel, and the other end of the spring being mounted upon a bracket swivelled on a rod extending through said support.

7. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, said means for urging the panel against the tone pin including a resilient element, supported between the panel and a rigid support mounted upon the cabinet, one end of said spring being mounted upon a bracket swivelly over a screw adjustably mounted on the panel, and the other end of the spring being mounted upon a bracket swivelled on a rod extending through said support, and a wedge-shaped member adjustably mounted on said rigid support and holding said rod in various positions to supplement the adjustment of the resilient action of the spring.

8. A sound distributing panel and baffle for loud speakers, comprising a cabinet, a panel mounted thereon and constructed of varying thickness, a tone pin mounted on said cabinet

and engaging said panel for holding it under tension, means for urging the panel against said tone pin, and a loud speaker mounted on said panel, said cabinet being of any desired design.

9. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, said panel being designed so that different portions thereof are adapted to vibrate at predetermined natural frequencies.

10. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, said tone pin comprising a rod supported upon a rigid support mounted on said cabinet, and the front end of said rod engaging against a strip secured upon the rear face of the panel.

11. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, said tone pin comprising a strip engaging against the panel and mounted on a support member which is in turn mounted upon said cabinet.

12. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, the field of the loud speaker being supported from the cabinet, and the coil of the loud speaker being mounted on said panel.

13. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, said panel being of balsa wood.

14. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, said panel being of balsa wood, and the loud speaker being spaced by a cushioning member from the said panel.

15. A sound distributing panel and baffle for loud speakers, comprising a cabinet, a panel mounted thereon and constructed of varying thickness, a tone pin mounted on said cabinet and engaging said panel for holding it under tension, means for urging the panel against said tone pin, and a loud speaker mounted on said panel, said panel being of balsa wood, grille mounted on said panel opposite the loud speaker, both the grille and the loud speaker being spaced

by a cushioning member from the said panel to keep the grille and the loud speaker in cushioned or floating condition.

16. A sound distributing panel and baffle of balsa wood for loud speakers, comprising a cabinet, a panel mounted thereon and constructed of varying thickness, a tone pin mounted on said cabinet

and engaging said panel for holding it under tension, means for urging the panel against said tone pin, a sound insulated grille and a sound insulated loud speaker mounted on said panel, said grille being in juxtaposition with said loud speaker.

WILLIAM J. MAXWELL.
